UNITED STATES PATENT OFFICE.

LESLIE G. SHARP, OF CHICAGO, ILLINOIS.

ROOFING-TILE.

SPECIFICATION forming part of Letters Patent No. 787,474, dated April 18, 1905.

Application filed June 9, 1904. Serial No. 211,764.

To all whom it may concern:

Be it known that I, LESLIE G. SHARP, a citizen of the United States, residing at Chicago, in the county of Cook and State of Illinois, have invented a new and useful Improvement 5 in Roofing-Tiles, of which the following is a specification.

My invention pertains more particularly to roofing-tile made of plastic clay or shale suitably shaped and burned in a kiln, although cement or any other plastic material that may be found well enough adapted to such purpose may be used in their manufacture without subjecting them to the aforesaid burning 15 process.

My invention does not relate to what are commonly known as "interlocking" roofing-tiles of the kind that have a shallow groove or gutter on the face side of the tile at one side 20 and a short tongue made on the under part of the tile extending along the other side thereof and adapted to fit down into said groove or gutter, so as to interlock and connect the tiles side by side in forming a roof and to prevent 25 leakage; but my invention does relate to tile of the kind that overlap each other at their side joints by means of upwardly and downwardly projecting marginal parts or flanges made on the sides of the tile, and, as herein 30 shown, my invention more particularly relates to such patterns of tile as have a face or body part made up of curves or a combined curved and flat surface which are commonly called "S" or "Spanish" patterns. Such tile 35 are usually made with an upwardly-projecting marginal side flange so low or short that with a little snow or ice on the tile when it rains the water is liable to flow over the top, causing the roof to leak, and such simple poorly-fitting 40 short lap-joints afford but slight protection against wind-driven snows and rains. Furthermore, by reason of four thicknesses of the tile coming together at the corners where each four tile are assembled in forming 45 a roof a corner of one of the upper tile is usually cut off and a corner of one of the lower course of tile is also cut off to match the cut corner of the aforesaid upper tile, and they are then butted together, so as to 50 reduce the number of thicknesses, and there-

by render it possible to get the four tile together at that part and without making a clumsy joint; but such cutting away of the corners at the lap part of the tile makes such a short open joint at the corners that even under ordinary conditions the roof is liable to leak, to say nothing of the severe tests it must undergo when subjected to wind-driven snows and rains. To make these tile on the interlocking plan hereinbefore mentioned also 55 produces very poor and unsatisfactory corner-joints, and the side joints being made so low down water flowing into the grooves or gutters and freezing is liable to burst the outside wall of the groove, and thus cause 60 leakage, or with ice forming in the grooves or if leaves and dirt lodge therein and rains come the water is quite liable to go over the side of such shallow grooves or gutters and cause the roof to leak badly. For the reasons above stated it may be clearly seen that roofing-tiles made with such short simple overlapping or interlocking low-down side joints cannot make a roof that may be fully 65 depended upon under the various conditions 70 that must usually be provided for.

The object of my invention is to produce a roofing-tile that will be light, cheap to manufacture, beautiful in appearance, with long overlapping side joints located well above the 75 lowermost part of the weather-exposed portion of the face of the tile and with all joints so well constructed and amply protected that the tile will make a roof that cannot be otherwise than both water and snow proof and 80 thoroughly reliable under the most severe and exacting conditions.

My improved roofing-tile is hereinafter more fully described and claimed.

In the accompanying drawings, illustrating 85 my invention, similar letters refer to similar parts throughout the several views.

Figure 1 is a plan view of four of my improved roofing-tiles assembled as in forming a roof, and in this view it will be seen that 90 the outside or gable tiles A' differ slightly from the tile A that are intended to form the inner or body of the roof. The convex-curved part of the gable-tile A' not having to join another tile, the outside part or flange thereof 95

is made plain, extends down to the roof foundation, and, as shown in this instance, has a tapering horizontal flange a formed on its side to make a better finish at the gable ends 5 of the roof. Fig. 2 is a lower end elevation of my gable-tile A' and a broken section of the tile A. This view also shows in position my eave-closing piece B' and a section of my eave-closing pieces B, each of said eave-closing 10 pieces being made, as shown, to fit the respective tile in which it is used. Fig. 3 is a view of one of my gable-tile with its upper end broken away and the tile shown in longitudinal section cut on line 3 3 of Fig. 2 and shows 15 a sectional view of my eave-closing piece B' in position and also shows a section of the perforated rib a' that is shown in Fig. 5. Fig. 4 is a plan view of the upper side or face part of one of my improved roofing-tiles A. 20 Fig. 5 is a plan view of the under side of one of my roofing-tiles A. Fig. 6 is a sectional view of parts of two of my roofing-tiles joined together and as cut on line 6 6 of Fig. 1. Fig. 7 is a perspective plan view of a portion of 25 two of my roofing-tiles assembled and as looking at the upper ends thereof, this view being to more clearly show the inwardly-jogged portion of one tile and the outwardly-projecting part of another and shows how these parts 30 fit together. Fig. 8 is a sectional end-elevation view of parts of two of my tiles assembled and as cut on line 8 8 of Fig. 4. Fig. 9 is a sectional end-elevation view of parts of 35 four of my tiles assembled and as cut on line 9 9 of Fig. 4. Fig. 10 is a sectional end-elevation view of parts of four of my tiles assembled and as cut on line 10 10 of Fig. 4. Fig. 11 is a longitudinal sectional view of parts of 40 two of my tiles assembled and as cut on line 11 11 of Fig. 4. Fig. 12 is a sectional end elevation of parts of two of my roofing-tiles assembled and as cut on line 12 12 of Fig. 5 and also shows one of my eave-closing pieces 45 B in position. Fig. 13 is a cross-sectional view of parts of two of my tiles assembled to show a slightly-modified form of a lap side joint. Fig. 14 is a plan view of a modified form of one of my roofing-tiles, showing its face portion made up of a convex part joined 50 to a horizontal or flat part. Fig. 15 is a cross-sectional view of one of my modified tile shown in Fig. 14 and a portion of another as cut on line 15 15 of Fig. 14.

My roofing-tile A is preferably made with 55 its body part composed of a convex portion a^2 and a concave portion a^3 , joined as shown in Fig. 4. At its side near one of its upper corners the body part has an inward jog a^4 , and on the opposite side at the other upper 60 corner I make an outwardly-projecting somewhat box-shaped part a^5 . The upper end of the tile has a downward jog a^6 , making the convex part a^2 a little shorter in length than the concave part a^3 . On said concave part, 65 as shown in Fig. 4, I make an upwardly-pro-

jecting marginal part or flange a^7 , which extends from the lower end of the tile along its side to the upper end thereof, jogging around the lower end a^8 and corner a^9 of the outwardly-projecting part a^5 , as shown, and at a point 70 below the top of the part or flange a^7 I sometimes form a step a^{10} , which, as shown in this instance, extends from the lower end of the tile to the outwardly-projecting part a^5 , and I in some cases make a similar step a^{11} in 75 the said upwardly-projecting marginal part or flange a^7 inside of said outwardly-projecting part a^5 , said step extending from the lower to the upper end thereof or to the upper end of the tile. At the upper end of the tile I 80 preferably make an upwardly-projecting marginal flange a^{12} , which extends from one side of the tile to the other following the contour of said downwardly-jogged part a^6 in the end of the convex part a^2 . Down through an enlarged part a^{13} of said upwardly-projecting marginal flange a^{12} I make a nail-hole a^{14} , and a short distance below said upwardly-projecting marginal flange a^{12} I usually make an upwardly-projecting cross-rib a^{15} , which extends 85 from one side of the tile to the other, excepting when I make a water-escape opening a^{16} , as shown in Fig. 4, which cuts the said rib in two parts at that point. In this instance it will be seen that the shorter part of the aforesaid upwardly-projecting cross-rib a^{15} extends clear up to the inside of the upwardly-projecting marginal part or flange a^7 and is joined thereto in the outwardly-projecting part a^5 hereinbefore described. In tiles made by 90 others such cross-ribs are usually terminated or cut off down on a much lower level of the tile, because in their construction it would interfere with other parts in assembling the tile and just where such a cross-rib is most badly 95 needed to properly protect the joints. Where the corners of four tiles come together, there is no cross-rib.

On the convex part a^2 of the tile I make a downwardly-projecting marginal part or 100 flange a^{17} , which extends from the lower to the upper end of the tile following the contour of the inwardly-jogged part a^4 , as shown in the inverted view of my tile in Fig. 5. In some cases I make a longitudinal bead or nose 105 a^{18} along the outer corner of the bottom of said downwardly-projecting flange a^{17} , which bead or nose part a^{18} is clearly shown in Figs. 3, 4, and 6. In the bottom of said downwardly-projecting marginal part or 110 flange a^{17} at the end of the cross-rib a^{15} I make a groove or notch a^{19} , which is clearly shown in Fig. 5, and in some instances I make on the bottom of said downwardly-projecting marginal part or flange a^{18} a downwardly-projecting part a^{20} , which, as here shown, is intended to go down into the opening a^{21} of another tile, as shown in Figs. 4 and 8, when the tiles are assembled.

To better close and protect the joint-opening 130

when two tiles are joined together, I may make on the under side of the tile a longitudinally-disposed downwardly-projecting closing-rib a^{22} , as shown in Figs. 5 and 6, and also make a 5 rib a' , with a hole a^x through it, as shown in Figs. 3 and 5, and may provide another rib, a^{23} , both of said ribs being made on the under side of the convex part a^2 to strengthen and stiffen the same and the hole a^x being made 10 for inserting a wire (not shown) for securing the lower end of the tile to the roof foundation, as is frequently done in laying tiles on steel or iron purlins C or skeleton construction, where there are no sheathing-boards to 15 which the tile may be nailed. At the upper end of the tile, on the bottom or under side, I may make a downwardly-projecting lug a^{24} , (shown in Figs. 5, 7, and 11,) which lug is to hook over a purlin C, as shown in Fig. 11 and 20 as is commonly done in laying roofing-tiles. On the lower end of my tile I usually make a downwardly-projecting marginal cross-flange a^{25} , as shown in Figs. 5 and 2, which cross-flange a^{25} , as shown in Fig. 2, jogs 25 around the stepped part a^{10} , and to receive this irregular shape or contour at a^{26} when the tiles are assembled to form a roof a groove a^{27} is made in the inwardly-jogged part a^4 , as is clearly shown in Figs. 4, 5, and 7. Located 30 above the said marginal cross-flange a^{25} and parallel thereto I preferably make a downwardly-projecting rib or tongue a^{28} , as shown in Figs. 5, 3, and 11, which tongue projects down between the upwardly-projecting marginal flange a^{12} and cross-rib a^{15} of a 35 similar tile when the tiles are assembled in roof construction, and said downwardly-projecting marginal flange a^{25} fits down over the outside of the said cross-rib a^{15} of the tile laid 40 below it, as best shown in Fig. 11. In this construction I show a recess or groove a^{29} in the bottom of the tile in Fig. 5, which groove is made to receive the widened-out part a^{30} of the upwardly-projecting marginal flange a^{12} 45 of a similar tile when assembled as a roof. In some cases I cut away a portion of the upwardly-projecting marginal flange at a^{31} , Fig. 4, to enable that part of the downwardly-projecting flange a^{25} at a^{32} to project down below 50 the top of said upwardly-projecting marginal flange a^7 and to afford better protection for the end of the joint, as shown partly in dotted lines in Fig. 2.

As the convex part a^2 of my outer or gable 55 tile A' does not connect with another tile, its outside part is made plain and comes down to the roof foundation D, as shown in Figs. 1 and 2, and in some cases I add a tapering horizontal flange part a to make a better or 60 straight-line finish at the gable end of the roof. At the opposite gable a straight-line finish can be made by using in connection with the regular tile some sections of similar tile modified to suit the case and with the horizontal 65 flange part a added to said section-pieces when necessary. To prevent sparrows or birds from nesting therein and to prevent snow and rain from blowing into the open ends of the convex part of the bottom or eave course of tile, I preferably make a separate eave-closing 70 piece B, which may have a marginal rib b , and said eave-closing piece is made of a shape to fit the inner curve of the convex part of the tile and also adapted to fit into the groove between the downwardly-projecting marginal 75 cross-flange a^{25} and the downwardly-projecting rib or tongue a^{28} , as shown in Figs. 2, 3, and 12. The downwardly-projecting marginal cross-flange a^{25} and the downwardly-projecting rib or tongue a^{28} serve to securely hold the eave-closing piece in an upright position and so it cannot get out of the tile. This not only makes a neat and good eave-closing device, but renders unnecessary the making of special tiles with burned-in ends, as 80 commonly done, which are difficult and expensive to make and can be used only for the bottom or eave course of tile in constructing a roof. The upwardly-projecting marginal part or flange a^7 is preferably curved 85 to fit the inner curve of the downwardly-projecting marginal part or flange a^{17} of the convex part of the tile; but in some cases I may make the inner curve of the upwardly-projecting marginal part or flange a^7 concave, as 90 shown in Fig. 13, so as to leave an elliptical-shaped opening E between the two flanges a^7 and a^{17} to prevent capillary attraction of any water that may get into the joint if in any case it should be found necessary to have such a 95 safeguard. The downwardly-projecting part a^{20} (shown in Figs. 4 and 7) is for the purpose of closing the upper end of the stepped part joint, so that any water getting into the groove a^{27} cannot run down lengthwise in the joint 100 of the stepped part a^{10} , but instead will be led down into the concave part of the tile.

As Spanish and S tiles are commonly made by others where an upwardly-projecting marginal flange is made at the upper end 105 of the tile the height of said flange diminishes greatly as it goes down on the outer side of the convex part of the tile, and right in the corner where four tiles come together and where a good height of marginal flange 110 is most badly needed to properly protect the corner-joints the flange is usually cut entirely off or so very low that it is practically worthless for the purpose of making a safe corner-joint. In my construction it will be seen that 115 four tiles can come together at their corners without having any of either the upwardly-projecting flange a^{12} or of the upwardly-projecting cross-rib a^{15} cut away or in the least diminished in height where a good width or 120 height of such parts is so necessary to protect the corner-joints. It will also be seen that as 125 my tile are constructed each upwardly-projecting marginal flange a^{12} , upwardly-projecting cross-rib a^{15} , downwardly-projecting 130

flange a^{25} , and downwardly-projecting tongue a^{28} is made to connect directly with a like part on another tile, so as to form practically continuous ribs or flanges clear across the roof 5 when the tile are assembled, excepting at the points where the water-escape openings a^{16} are made in the upwardly-projecting cross-ribs a^{15} . It will be seen that the water-escape opening a^{16} is sufficiently closed below by the 10 downwardly-projecting marginal cross-flange a^{25} and also closed above by the downwardly-projecting rib or tongue a^{28} , although any water that may happen to get up between the upwardly-projecting cross-rib a^{15} and the upwardly-projecting marginal flange a^{12} can leak 15 out under the downwardly-projecting rib or tongue a^{28} and the downwardly-projecting marginal cross-flange a^{25} to the exposed face part of the tile and run off.

20 Instead of making the body or face of my tile of a concavo-convex-curved form I sometimes make it with a convex part a^2 , joined to a flat or horizontal part A^2 , as shown in Figs. 14 and 15; but the other features of this modified form of tile are similar to those of the concavo-convex-curved form hereinbefore described.

25 While I have shown and described the preferred form of my invention, I do not wish to be limited thereto, as many slight modifications could be made without departing from the spirit of my invention.

30 What I claim as my invention, and wish to secure by Letters Patent, is—

35 1. An improved roofing-tile, having a body part made with the greater portion of its two sides parallel to each other, an inward jog made in one of said sides in an upper corner of said body part, an outwardly-projecting part made on the other of said sides in the opposite upper corner of said body part, said outwardly-projecting part adapted to receive the inwardly-jogged overlapping part of a similar tile when such tile are laid together in 40 forming a roof, a downwardly-projecting marginal part or flange made on said body part and extended along the same side thereof that has the said inward jog and following the contour of said inward jog to the upper end of the body part, an upwardly-projecting marginal part or flange made on said body part and extended along the same side thereof that has said outwardly-projecting part and jogged around the lower end and corner of said outwardly-projecting part to the upper end of said body part, and suitable means for securing said tile to a roof foundation, all when made substantially as described and for the purposes set forth.

45 2. An improved roofing-tile, having a body part made with the greater portion of its two sides parallel to each other, an inward jog made in one of said sides in an upper corner of said body part, an outwardly-projecting part made on the other of said sides in the

opposite upper corner of said body part, said outwardly-projecting part adapted to receive the inwardly-jogged overlapping part of a similar tile when such tile are laid together in forming a roof, a downwardly-projecting marginal part or flange made on said body part and extended along the same side thereof that has the said inward jog and following the contour of said inward jog to the upper end of the body part, an upwardly-projecting marginal part or flange made on said body part and extended along the same side thereof that has the outwardly-projecting part and following the contour of said outwardly-projecting part to the upper end of said body part, the notch or recess a^{19} , made in said downwardly-projecting marginal part or flange, an upwardly-projecting marginal flange made on the said body part and extended across the upper end thereof, an upwardly-projecting cross-rib made on the body part but located below the said upper end marginal flange, and means for securing said tile to a roof foundation, all when made substantially as described and for the purposes set forth.

50 3. An improved roofing-tile, having a body part with the greater portion of the two sides thereof made parallel to each other, one of said sides made of convex-curved form, an inward jog made in said convex-curved part at the upper corner of said body part, an outwardly-projecting part made on the other of said sides in the opposite upper corner of said body part, said outwardly-projecting part adapted to receive the inwardly-jogged overlapping part of a similar tile when such tile are laid together in forming a roof, a downwardly-projecting marginal part or flange made on said body part and extended along the same side thereof that has the said inward jog and following the contour of said inward jog to the upper end of the body part, an upwardly-projecting marginal part or flange made on said body part and extended along the same side thereof that has the outwardly-projecting part to the upper end of said body part, a downwardly-projecting marginal flange made on said body part and extended across the lower end thereof, the transverse groove a^{27} , made in said convex-curved part, and suitable means for securing said tile to a roof foundation, all when made substantially as described and for the purposes set forth.

55 4. An improved roofing-tile, having a body part made with the greater portion of its two sides parallel to each other, an inward jog made in one of said sides in the upper corner of said body part, an outwardly-projecting part made on the other of said sides in an opposite upper corner of said body part, said outwardly-projecting part adapted to receive the inwardly-jogged overlapping part of a similar tile when such tile are laid together in forming a roof, a downwardly-projecting marginal part or flange made on said body

- part and extended along the same side thereof that has the said inward jog and following the contour of said inward jog to the upper end of the body part, an upwardly-projecting 5 marginal stepped part or flange made on said body part and extended along the same side thereof that has the outwardly-projecting part, the downwardly-projecting tongue or part a^{20} , made on the bottom of said downwardly-projecting marginal flange, the groove a^{20} , made in said body part, an upwardly-projecting marginal flange made on said body part and extended across the upper end thereof, a downwardly-projecting marginal flange 10 made on the body part and extended across the lower end thereof, and suitable means for securing said tile to a roof foundation, all when made substantially as described and for the purposes set forth.
- 15 5. An improved roofing-tile, having a body part made with the greater portion of its two sides parallel to each other, an inward jog made in one of said sides in an upper corner of said body part, an outwardly-projecting part made on the other of said sides in the opposite upper corner of said body part, said outwardly-projecting part adapted to receive the inwardly-jogged overlapping part of a similar tile when such tile are laid together in 20 forming a roof, a downwardly-projecting marginal part or flange made on said body part and extended along the same side thereof that has the said inward jog and following the contour of said inward jog to the upper end of the body part, an upwardly-projecting marginal stepped part or flange made on said body part and extended along 25 the same side thereof that has the said inward jog and following the contour of said inward jog to the upper end of the body part, an upwardly-projecting marginal stepped part or flange made on said body part and extended along 30 the same side thereof that has the outwardly-projecting part and following the contour of said outwardly-projecting part to the upper end of said body part, an upwardly-projecting marginal flange made on said body part and extended across the upper end thereof, a downwardly-projecting marginal cross-flange made on the lower end of said body part, a downwardly-projecting rib or tongue made on the under side of said body part located above, but near and parallel to said last-mentioned downwardly-projecting marginal cross-flange, the recess a^{20} , made in the under side of said body part, and suitable means for securing said tile to a roof foundation, all 35 when made substantially as described and for the purposes set forth.
- 40 6. An improved gable-roofing tile, having a body part made with the greater portion of its two sides parallel to each other, a convex curve in its face, an outwardly-projecting part made in an upper corner of said body part, a downwardly-projecting part made on the convex 45 portion of said body part and extended along the side thereof to the upper end of the body part, the horizontal flange a , made on said
- downwardly-projecting part, an upwardly-projecting marginal part or flange made on said body part and extended along the same side thereof that has the outwardly-projecting part and following the contour of said outwardly-projecting part to the upper end of said body part, an upwardly-projecting marginal flange made on said body part and extended across the upper end thereof, a downwardly-projecting marginal cross-flange made on the lower end of said body part, and suitable means for securing said tile to a roof foundation, all when made substantially as described and for the purposes set forth. 50
7. An improved roofing-tile, having a body part made with its face of a joined concave and convex curved form, the sides of said body part made parallel to each other, an inward jog made in one of said sides in the convex part at an upper corner of said body part, an outwardly-projecting part made on the other of said sides in the opposite upper corner of said body part, said outwardly-projecting part adapted to receive the inwardly-jogged overlapping part of a similar tile when such tile are laid together in forming a roof, a downwardly-projecting marginal part or flange made on said body part and extended along 55 the same side thereof that has the said inward jog and following the contour of said inward jog to the upper end of the body part, an upwardly-projecting marginal stepped part or flange made on said body part and extended along 60 the same side thereof that has the outwardly-projecting part and following the contour of said outwardly-projecting part to the upper end of said body part, an upwardly-projecting marginal flange made on said body part and extended across the upper end thereof, a downwardly-projecting marginal cross-flange made on the lower end of said body part, a downwardly-projecting rib or tongue made on the under side of said body part located above, but near and parallel to said last-mentioned downwardly-projecting marginal cross-flange, the recess a^{20} , made in the under side of said body part, and suitable means for securing said tile to a roof foundation, all 65 when made substantially as described and for the purposes set forth. 70
8. In testimony whereof I have signed my name to this specification in the presence of two subscribing witnesses.
